(57) **CLAIM**

The ornamental design for a sample collection tube, as shown and described.

DESCRIPTION

FIG. 1 is a top perspective view of a sample collection tube;

FIG. 2 is a bottom perspective view thereof;

FIG. 3 is a front view thereof;

FIG. 4 is a back view thereof;

FIG. 5 is a left-side view thereof;

FIG. 6 is a right-side view thereof;

FIG. 7 is a top view thereof; and,

FIG. 8 is a bottom view thereof.

The broken lines depict portions of the sample collection tube that form no part of the claimed design.

1 Claim, 8 Drawing Sheets(56)
